UNITED STATES PATENT OFFICE

PAUL F. GOETZ, OF LOCKPORT, ILLINOIS

WATER HEATER

Application filed December 24, 1930. Serial No. 504,567.

This invention relates to improvements in water heaters.

One of the objects of the present invention is the provision of a water heater wherein 5 a direct heating method can be used or waste heat from the exhaust of Diesel motors, reverberating furnaces, gas engines and the like can be utilized for heating the water and the circulation of the waste heat is such that the 10 maximum amount of heat can be obtained from this waste before being discharged from the heater.

Another object of the present invention is the provision of a water heater employing 15 a lower water chamber with an upper steam chamber connected by vertical pipes with a combustion chamber arranged centrally of the device with a series of pipes therein communicating with the water chamber so that, 20 upon supplying of heat to the combustion chamber, the water within the pipes within the central combustion chamber will be heated and carried upwardly into the steam chamber where it will be conveyed back through 25 suitable vertical pipes to the water chamber.

A further object of the present invention is the provision of an improved type of water heater wherein either direct heat or waste heat can be utilized and includes improved 30 means for creating a circulation of the waste heat in such a manner as to obtain the maximum efficiency of the same and wherein the water circulation is such as to obtain the maximum heat through its circulation and to provide 35 a heater which can be used as a water heater for the heating of water or for heating a building or individual room.

With the above and other objects in view, the invention consists in the novel features of 40 construction, the combination and arrangement of parts hereinafter more fully set forth, pointed out in the claims and shown in the accompanying drawings, in which:

Figure 1 is a vertical sectional view, taken 45 through my improved water heater;

Figure 2 is a side elevation, with parts broken away and illustrated in cross section;

Figure 3 is a transverse sectional view;

Figure 4 is a top plan view;

Figure 5 is a side elevation, with parts in 50 section illustrating a slightly modified form of the invention;

Figure 6 is a horizontal section of the form 55 illustrated in Figure 5; and

Figure 7 is a diagrammatic view of the circulating members.

Referring more particularly to the drawings, 1 indicates a cylindrical outer shell connected by means of the head plates 2 and 3. Beneath the head plate 3 is a water chamber 4 and above the head plate 2 is a steam chamber 5. Arranged centrally of the shell 1 is a housing 6, which forms a central combustion chamber and arranged around the inner wall of the housing 6 are the tubes 7, the ends of 60 which pass through the plates 2 and 3 and form direct communication between the water chamber 4 and the steam chamber 5.

Disposed between the plate 3 and the bottom of the water chamber 4 is a burner housing 10 having arranged therein a burner 11, which is preferably adapted for liquid fuel. The upper end of the burner chamber 10 opens into the lower end of the combustion chamber A and the upper end of the combustion chamber A opens out through a tube 12 arranged between the plate 3 and the upper wall of the steam chamber 5. A restricted outlet opening 13 communicates with the tube 12 for discharging the gases of the 65 burned fuel.

Depending from the head 14 of the tube 12 is a superheater coil 15, which extends downwardly into the combustion chamber A, as shown in Figure 1.

When liquid fuel, such as coal oil and the like, is used in the burner 11, the heat therefrom has a tendency to heat the vertical pipes 7 within the housing 6, the heated water rising 70 upwardly to the chamber 5. A circular 75

conduit 16 is arranged within the steam chamber 5 and encircles the annular formation of the upper ends of the pipe 7, as shown in Figure 1, thereby forming sump or receptacle-like part between the lower end of the tube 12 and the conduit 16 into which the hot water from the upper ends of the pipes 7 will be deposited, the steam from the hot water rising upwardly in the chamber 5 and, as the water continues its upward movement, it will flow over the top of the conduit 16 and be evenly distributed into the upper ends of the pipes 9, where it will travel downwardly and return to the water chamber 4.

The tubes 9 within the housing 8 can also be heated to create a circulation of water by providing an inlet 17 at the lower end of the housing 8 and at one side thereof. Water from this inlet leads into the housing 8 at a point 18 above the plate 3 and then is directed against an inclined partition 19, which carries it upwardly onto a circular plate 20 which in turn continues around the housing 6 and leads onto a second inclined portion 19'. From the inclined portion 19', the heat is guided upwardly and around the housing 6 again by an upper circular plate 20' which, in turn, leads onto a third inclined portion 19a. From the inclined portion 19a, the heat is guided upwardly and around the housing 6 again by a third circular plate 21 onto a fourth inclined portion 19b to the outlet 17'.

Waste gases such as exhaust gases from internal combustion engines or similar heated gases can be used for circuitous distribution between the housing 6 and the outside shell 8 where the heat will be brought into direct contact with the tubes 9 for heating the same. When the tubes 9 are heated, the water there-

in rises upwardly into the chamber 5 where

it will flow over the conduit 6 and return to the water chamber 4 through the tubes 7.

It will be apparent from the construction described and illustrated that either direct heating arrangement by means of the heater 11 can be used or waste heated gases can be used for circulation within the space between the shell 8 and the housing 6, thus providing a heater which can be used for a great many purposes.

In Figures 5, 6 and 7, I have illustrated a slightly modified form of the invention wherein the outer shell 8' is spaced from the inner shell 6' to form a circulation chamber between these two shells and within this chamber I provide the tubes 9' while within the housing 6' are the tubes 7' which connect the steam chamber 5' and water chamber 4'.

Arranged in spaced relation within the chamber between the tubular housing 6' and 8' are the vertically extending panels 22 and 23, which are arranged in equal spaced relation, as shown in Figure 6. In the arrangement of these panels 22 and 23, it will be noted that panels 23 extend from the bottom plate

3' upwardly to a point spaced from the top plate 2' while panels 22 extend downwardly from the top plate 2' to a point spaced from the bottom plate 3' thus causing any gases passing in through the inlet 24 to rise upwardly and over the top of the first panel 23. They are thence guided downwardly around the lower end of a panel 22 and again upwardly where the same circulation of the heated gases continue throughout the several chambers formed by the panels until the gases reach the outlet 24'. This circulation of heated gases through the chamber formed by the inner housing 6' and the outer shell 8' will thoroughly heat the water in the tubes in this chamber.

It will be apparent from the foregoing that a great many ways can be employed for creating a circulation of heated gases around the water tubes between the lower water chamber and the upper steam chamber, the main feature of the invention being the provision of a water heater wherein liquid fuel can be used as a direct heating element or waste gases or heat fumes can be used equally as well, thus reducing to a minimum the expense incurred for operating a heater of this character, which is comparatively simple and it is believed the same can be manufactured and installed at a very low cost.

I claim:

1. A heater of the class described including, an annular water chamber and an annular steam chamber spaced therefrom, a shell having a hot gas inlet and outlet positioned between said chambers, a housing within the shell between the chambers, tubes extending from the water chamber to the steam chamber between the shell and housing, a second set of tubes within the housing and extending between the water chamber and steam chamber, and burner means to provide for heating of the second set of tubes when the flow of hot gas to said first set is interrupted.

2. A heater of the class described including, an annular water chamber and an annular steam chamber spaced therefrom, a shell having a hot gas inlet and outlet positioned between said chambers, means arranged between the chambers to provide passageways, a housing within the shell between the chambers, tubes extending from the water to the steam chamber between the shell and housing, a second set of tubes within the housing and extending between the water chamber and steam chamber, and burner means to provide for the heating of the second set of tubes when the flow of hot gas to said first set is interrupted.

3. A heater of the class described including, an annular water chamber and an annular steam chamber spaced therefrom, a shell having a hot gas inlet and outlet positioned between said chambers, means within the shell forming a circuitous guide between the inlet

and outlet, a housing within the shell between the chambers, tubes extending from the water chamber to the steam chamber between the shell and housing, a second set of tubes with 5 in the housing and extending between the water chamber and steam chamber, and burner means to provide for the heating of the second set of tubes when the flow of hot gas to said first set is interrupted.

10 In witness whereof, I have hereunto set my hand this 1st day of November, A. D. 1930.

PAUL F. GOETZ.
